UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-BOTTOM.

1,396,801.

Specification of Letters Patent.

Patented Nov. 15, 1921.

Application filed October 16, 1916, Serial No. 125,976. Renewed July 1, 1920. Serial No. 393,456.

To all whom it may concern:

Be it known that I, ERASTUS E. WINKLEY, a citizen of the United States, residing at Lynn, in the county of Essex and State of Massachusetts, have invented certain new and useful Improvements in Shoe-Bottoms; and I do hereby declare the following to be a full, clear, and exact description of the invention, such as will enable others skilled in the art to which it appertains to make and use the same.

This invention relates to boots and shoes, and particularly to that part of a boot or shoe which includes the outsole and the heel and is commonly described as the "bottom."

It has been proposed, in the manufacture of certain styles of boots and shoes, to employ an outsole which is shorter than the shoe as a whole, this sole being of the usual form and character from the toe to the rear end of the shank-portion, but extending thence only in the form of a short tongue or projection of less width than the shank-portion. In connection with this sole a heel is used which is provided, on its upper surface, with a recess shaped to receive and fit the tongue on the sole, so that the upper surfaces of the heel and sole are continuous. In a shoe so constructed the outsole is secured in place upon the insole in any usual manner and the heel is then nailed to the shoe, in which case the greater part of the heel-seat of the shoe is formed by the lower surface of the insole, instead of wholly by the outsole as in the more common construction.

The object of the present invention is to improve the formation of the soles and heels of boots or shoes constructed in the manner just set forth, to the end that the lateral margins of the sole, at the junction with the heel, shall be adequately supported, and that the recess in the heel may be conveniently formed without unduly weakening or defacing the heel at its breast corners, while at the same time the form of the adjoining parts is such as to insure correct registration between the heel and the sole, particularly in a transverse direction, in order to present a full unbroken lateral surface.

To the foregoing end it is proposed to form the tongue on the sole, and the recess in the heel which receives this tongue, as set forth hereinafter in connection with the de-

scription of the illustrated embodiment of the invention.

In the accompanying drawings Figure 1 is a plan-view of a heel and a sole, before attachment to the shoe, formed in accordance with the present invention and assembled in the relative position which they occupy in a completed shoe; Fig. 2 is a section on the line 2-2 of Fig. 1; Fig. 3 is a perspective view of a heel formed in accordance with this invention, showing the seat-surface of the heel; Fig. 4 is a perspective view of the rear end of a sole formed in accordance with the invention, the sole being inverted to show its lower or grain surface, and Fig. 5 is a section on the line 5-5 of Fig. 1.

The invention is illustrated as embodied in a shoe-bottom comprising a heel and an outsole, and the heel is shown as being built up of layers or lifts of leather or leather-board, though it will be understood that the use of such materials, and the formation of the heel in the illustrated manner, are not essential to the present invention. The heel may be formed upon any ordinary or suitable pattern in all respects except as to its seat-surface. Of this seat-surface the major portion 11 is of the usual smooth, concave form, adapted to fit against the slightly convex heel-seat of the shoe. The characteristic feature of the invention is found, however, in a recess 12 which is formed at the breast-end of the seat-surface of the heel. This recess extends rearwardly from the breast of the heel, and it terminates laterally in curved margins 13 which converge toward the rear extremity of the recess. This rear extremity is formed by a margin or shoulder 14, which may be straight, as illustrated.

The lateral margins 13 are inwardly convex, and they extend to the breast corners 15 of the heel. Accordingly, while the recess is, at its forward extremity, of the full width of the heel, the lateral surfaces of the heel are unbroken, and the unrecessed lateral portions 16 abreast of the recess increase rapidly in width from the front toward the rear of the recess. At its central portion, and at its rear extremity, the depth of the recess is of the full thickness of the sole to be received therein, as shown in Fig. 2.

The sole is formed, to the rear extremity 105 of the shank-portion 17, in accordance with

any usual or suitable pattern, and the rear extremity of the shank-portion is of the same width as the breast of the heel. Beyond the shank-portion the material of the 5 heel extends in the form of a rearwardly tapering projection or tongue 18 of less length than the usual heel-seat, which is shaped to conform substantially to the recess in the heel which has just been described.

10 For this purpose the projection is provided with concave curved lateral edges 19, and with a straight rear edge 20, corresponding, respectively, with the curved margins 13 and the straight margin 14 of the recess. The 15 central portion of the tongue, including its rear edge, is of the same thickness as the remainder of the sole to fill the recess 12 and produce a flush heel seat.

The form or outline of the recess and 20 the sole-projection just described has several advantages. In the first place, the rear extremity of the projection and the recess, since the lateral edges and margins at this 25 point approximate parallel positions owing to the curvature of these parts, insure accurate lateral registration between the heel and the sole. This is of particular importance where the shoe is constructed in accordance with a mode of operation by which 30 the edge of the sole is trimmed prior to the application of the heel, and the heel is trimmed and finished prior to its application to the other parts of the shoe. In this mode of manufacture it is of great importance 35 that accurate lateral registration be secured in order that the finished surfaces of the heel and the sole shall unite in a smooth continuous surface, and the heel be correctly applied to the heel-seat of the 40 shoe.

In addition to the foregoing advantage, the present construction has the further advantage that the lateral edges of the shank of the sole are adequately supported at their 45 rear extremities, that is, where the sole joins the breast of the heel, whereas in previously proposed constructions, in which the rearward projection of the sole is of less width throughout than the heel, shoulders 50 are formed in the sole in the plane of the breast, resulting in corners, at the rear extremity of the shank, which are not directly supported upon the heel, and which, therefore, are liable to sag, when the shoe 55 is worn, so as seriously to impair its appearance. In the present construction this is avoided by carrying the lateral margins of the heel-recess outwardly to the breast corners of the heel, so that the sole is directly supported by the heel from the 60 middle to its corners.

The recess in the heel may be formed in any convenient manner, according to the material of which the heel is made. Where 65 the heel is made of comparatively yielding

material such as leather or its substitute, the recess is most conveniently made by compression of the material, suitable provision for this being made in the formation of the dies employed in the machine by which the 70 heel is compressed and shaped. Where the heel is formed in this manner it is undesirable to recess the heel to a great depth at points close to the breast corners and lateral surfaces of the heel, since to do so involves 75 a degree of distortion of the material which results in a shearing action and is liable to break down the material at its outer surface and visibly distort the layers of the material, while at the same time leaving thin 80 and weak edges at the angles between the breast and the lateral surfaces of the heel. Accordingly a feature of the present invention resides in a graduation of the depth of the recess 12, this recess having a depth 85 substantially equal to the full thickness of the sole at its middle portion and throughout its rear extremity, but being diminished in depth laterally, so that at the breast corners or angles 15 the depth becomes very 90 slight, the lower surface of the recess coinciding substantially with the seat-surface 11 of the heel at these points.

The sole-extension 18 is formed at its lateral margin to correspond in thickness with 95 the graduated depth of the heel-recess. For this purpose the material of the sole is preferably cut away, or notched, at the bottom or grain side, to provide two recesses 21 by which the thickness of the sole is tapered 100 to a thin edge laterally toward the angles 23, which correspond in position with the angles 15 of the heel. These notches are so formed as to produce square shoulders 22 which fit closely against the breast of the 105 heel and produce a close joint at this point, and a finished appearance which does not differ substantially from that of the more usual construction, except for the short vertical lines of cleavage where the lateral 110 edges of the shank-portion terminate in the plane of the heel-breast.

In the drawings no means are shown for securing together the sole and the heel, but it will be understood that these parts are 115 attached to the other parts of the shoe in the usual manner, the heel being nailed and the nails by which it is secured being passed through the projection 18 on the sole so as to fasten the sole and the heel securely together and produce a structure which is substantially as solid as one in which the sole 120 extends over the entire upper surface of the heel.

The nature and scope of the present invention having been indicated and its preferred embodiment having been specifically described, what is claimed as new, is:—

1. A shoe-heel having in its heel-seat surface, a pronounced recess below the general 130

- level thereof, for the reception of a sole, the recess extending from the breast-surface of the heel and being of less width than the heel except at its forward extremity, at 5 which point it is the full width of the heel.
2. A shoe-heel having in its heel-seat surface, a pronounced recess below the general level thereof, for the reception of a sole, the recess extending from the breast-surface of 10 the heel and being of less width than the heel except at its forward extremity, at which point it is substantially the full width of the heel, while the depth of the recess diminishes, from the middle portion, to- 15 ward the points where the lateral margins of the recess terminate at the breast.
3. A shoe-heel recessed, in its heel-seat surface; for the reception of a sole, the recess extending from the breast-surface of 20 the heel and being bounded, laterally, by curved margins which extend rearwardly from the corners of the heel, in converging directions, the curvatures of said margins being convex toward each other.
- 25 4. A shoe-heel recessed, in its heel-seat surface, for the reception of a sole, the recess extending from the breast-surface of the heel and being bounded, laterally, by curved margins which extend rearwardly 30 from the corners of the heel, in converging directions, the curvatures of said margins being convex toward each other, while the depth of the recess diminishes, from its middle portion, toward the points where the 35 lateral margins terminate at the breast.
5. A shoe-sole provided, at the rear of the shank-portion, with a projection of less length than the usual heel-seat bounded laterally by rearwardly-converging edges, the 40 lower or grain surface of the projection being notched to produce shoulders at the junction between the shank and the projection, which increase in depth toward the lateral margins.
- 45 6. A shoe-bottom, comprising a sole and a heel, said sole being provided, at the rear of the shank-portion, with a projection bounded laterally by rearwardly-converging edges, the lower or grain surface of the 50 projection being notched to produce shoulders, at the junction between the shank and the projection, which increase in depth toward the lateral edges; and said heel having, in its seat surface, a recess conforming 55 to said projection on the sole, the projection being seated in the recess with the upper surface of the sole and the seat-surface of the heel substantially continuous.
- 60 7. A shoe-bottom comprising a sole and a heel, said sole having at the rear end of its shank-portion a rearwardly-tapering tongue of the same thickness as the sole at its central portion and tapering in thick- ness outwardly at each side, and said heel having a recess at the breast-end of its seat- 65 surface shaped to receive said tongue with a breast-edge conforming to the lateral tapers of said tongue.
8. A shoe-bottom comprising a sole and a heel, said sole having at the rear-end of 70 its shank-portion a tongue tapering rearwardly from the full shank width and adapted to fit in a recess formed for its reception at the breast-end of the seat-surface of the heel, and the side portions of said 75 tongue being notched to provide shoulders against which the breast-corners of the heel abut.
9. A shoe-bottom comprising a heel and a sole, said heel having a recess at the 80 breast-end of its seat-surface shaped to receive a tongue portion of said sole, said tongue portion being notched on its lower or grain side to produce shoulders that abut against the breast-corners of the heel. 85
10. A shoe-bottom comprising a heel and a sole, the heel having at the breast-end of its seat-surface a recess extending the full width of the heel at the breast to receive a tongue portion of the sole, shaped to fill 90 said recess, whereby the tongue portion is firmly supported by the heel throughout its full width in the plane of the breast, the shape of the recess and tongue being such that the heel presents a full unbroken lateral 95 surface.
11. A shoe-heel having at the breast-end of its heel-seat surface a recess having a maximum depth at the middle portion of the heel and diminishing in depth gradually 100 toward both sides of the heel at the breast thereof in such manner that the ends of its forward edge substantially coincide with the breast corners of the heel.
12. A shoe-bottom comprising a short sole 105 and a heel, the heel end of said sole being of maximum thickness at the central portion thereof and diminishing gradually in thickness to a thin edge toward both sides thereof at the point where it joins the heel-breast, and said heel having at its breast-end a recess of corresponding shape to receive the end of the sole. 110
13. A shoe-bottom comprising a heel and a sole, said heel being provided at the breast-end of its heel-seat surface with a recess having a maximum depth at the middle portion of the heel and diminishing in depth gradually toward both sides of the heel at the breast thereof, and said sole having its 115 heel-end of corresponding shape to fit into said recess and being notched on opposite sides of its lower or grain side to produce shoulders that abut against the breast corners of the heel. 120
